RAIL ANCHOR

George L. Moore and James R. Steele, Owego,
N. Y., assignors, by mesne assignments, to Poor
& Company, Chicago, Ill., a corporation of
Delaware

Application December 18, 1945, Serial No. 635,668

3 Claims. (Cl. 238—327)

1

This invention relates to rail anchors and particularly to devices of this nature which are fabricated of short lengths of steel and so shaped or fashioned that they may be assembled with the rails which are to be anchored with the least possible use of force.

It has heretofore been proposed that rail anchors of this general type may with advantage be so made that, after each has been positioned upon the rail with which it is permanently associated, and comes into contact with the adjacent tie when such rail tends to move longitudinally of the roadbed, tilting of the anchor from its normally vertical plane may occur, thus causing in the usual case certain edges or corners of the anchor to bite into the metal of the rail and to thus increase the strength of the grip of the anchor on the rail.

A rail anchor which is so constructed that tilting under certain conditions may occur, is disclosed in Patent 1,890,066, granted to us December 6, 1932. While the anchor which comprises the subject matter of that patent has been found to be generally quite effective, and many have been used, its tendency to tilt under moderate load has been found to be disadvantageous rather than helpful, in many instances. Thus, excessive tilting under load has sometimes resulted in the transverse scoring or cutting of the rail surfaces. These transversely extending scores or cuts, while initially relatively unimportant, are considered to be objectionable because they may initiate fatigue failures in the rails. Cutting or scoring of the rail surfaces toward the outer margins of the rail flanges is particularly objectionable.

Again, the tilting of the anchor to an excessive degree ultimately destroys its capacity to grip the rail sufficiently tightly to prevent creeping, the metal of which the anchor is fabricated eventually becoming over-strained and its action as a resilient member being thus so reduced that the rail may slide through the anchor when a moderate creeping force is applied to the rail.

It is the primary purpose of the present invention to provide a rail anchor of the resilient and easily applied type, which has all of the numerous advantages of the anchor disclosed in the patent referred to without, however, having its disadvantages, the improved anchor being so designed and constructed that the tendency to tilt under load is very greatly reduced, the working efficiency of the anchor increased, the possibility of failure due to over-stressing of the metal of which it is fabricated almost eliminated, and its tendency to cut or score the rail surfaces

2

so far counteracted that such cutting or scoring very seldom occurs. These desirable results are achieved by so designing the anchor that it grips the rail in an improved manner without, however, being so materially changed in construction, as compared with the anchor previously patented, that any of the advantages of that anchor are sacrificed.

One important change in design results in the application of the principal lever gripping force of the anchor, during the presence of tilting pressure thereon to and over an area closely adjacent to the outer margin of the rail flange, instead of to and over an area of the fillet at the base of the rail web, as heretofore. The point or area to which the major downward lever pressure of the anchor upon the upper-surface of the rail flange is applied to thus lowered as far as possible toward the under-surface of the rail. The lever arm for delivering the last mentioned downward pressure is thus considerably shortened so as to exert a major gripping force and at the same time resist bending of the arm and consequent tilting of the anchor. Likewise, resistance to tilting is increased because of other factors, all to be hereinafter pointed out.

In the accompanying drawings, one embodiment of the invention is disclosed by way of example. It will be appreciated that minor changes may be made in the adaptation of the improved anchor to rails which differ somewhat in size and shape.

In the drawings,

Figure 1 shows in transverse section the base of a rail, with portion of the web, a rail anchor of the type above briefly described being shown loosely positioned on the rail as it would be just prior to the application of a force to drive the anchor into rail gripping position.

Figure 2 is a similar view showing, in full lines, the rail anchor in the position which it normally occupies when in use, and also showing in dotted lines the position to which its several portions would move were the rail to cease to offer resistance to contraction of the anchor, and

Figure 3 shows, in side elevation, a short section of rail, a portion of a rail supporting tie in elevation, one rail anchor in end elevation, and portion of a rail plate.

The portion of a standard rail which is illustrated in the drawings comprises the web 10 and the base flanges 11 and 12. The under-surface of the rail base, indicated at 13, is substantially flat and the upper-surfaces of the flanges 11 and 12 slope downwardly and outwardly from the

web 10 in the usual manner, these surfaces being indicated at 14 and 15, respectively, and making relatively small angles with the plane of the rail under-surface 13, for instance, angles of fourteen degrees, respectively. The upper margins of flange surfaces 14 and 15 merge with fillets 16 and 17 and the upper margins of these fillets merge with the lateral faces 18 and 19 of the web 10. Surfaces 20 and 21 may be designated rail flange edge surfaces.

The anchor is generally indicated at A and comprises a length of steel which is so fashioned in manufacture that it has the shape shown in the drawings. In cross section it may be rectangular as shown, and preferably is rectangular, with the longer cross-sectional dimension extending longitudinally of the rail to which it is applied, the disposition of the metal of the anchor in this manner, so that it is relatively wide, decreasing the possibility of tilting under load.

The invention contemplates, however, anchors which vary in transverse section, it being possible to fabricate the anchor of a length of metal channel shaped in cross section, or otherwise shaped, provided that the other conditions which the invention imposes are complied with.

The anchor comprises a number of portions, a terminal portion 30 adapted to overlie one flange of the rail, an intermediate portion 31 adapted to engage the under-surface of the rail approximately midway between its edges and preferably spaced nearer that edge opposite to the flange which is to be engaged by the terminal portion 30, a rail flange edge engaging terminal portion 32, a connecting portion 33 which connects the rail flange edge engaging portion 32 and the intermediate portion 31, and a loop portion 34 connecting the rail flange overlying portion 30 and the intermediate portion 31, this loop portion 34 extends downwardly below the under-surface of the rail and is adapted to engage the side surface of a tie 35, in some instances engaging the edge of the tie plate 36, as when the tie 35 becomes worn or where the tie plate projects beyond the side of the tie.

The connecting portion 33 is also preferably a loop which extends downwardly so as to be able to engage the side of a tie or the edge of a rail plate. The extreme terminal end of the rail flange engaging portion 32 is preferably upset so as to provide a bead or lip 37 adapted to overlie the immediately adjacent edge of the rail flange when the anchor is in operative position and to thus also tend to minimize tilting. The bead 37 is rounded as shown in Fig. 1 so as to present a smooth non-cutting surface to the adjacent bottom and corner portions of the rail.

The terminal portion 30 of the anchor is so formed that, when the anchor is in its effective position, it bears upon the upper-surface 14 of the underlying rail flange approximately at the location which is indicated at a in Figure 2 and 3, this location being immediately adjacent the edge of the rail flange. The end of the terminal portion 30 is preferably curved, as shown, to provide a complementary surface to engage the fillet 17. Between this curved surface, as indicated at b, and the location a previously referred to, a material portion of the under-surface of the anchor portion 30 is out of contact with the upwardly facing surface 14 of the rail flange when the anchor is in its operative position. As previously explained, the gripping action of the anchor on the rail is largely the result of the downward pressure of the portion

30 of the anchor at the location a and the upward pressure of the intermediate portion 31 of the anchor against the under-surface of the rail. The spacing of the portion 30 inwardly from the rail base intermediate said areas a and b permits the bearing surfaces associated with said areas to seat independently of each other on the rail and thereby makes possible the application of said major downward lever pressure at the location a. This result is obtained by reason of the fact that the portion 30 intermediate the bearings a and b is flexed downwardly toward the rail base, when the anchor is subjected to tilting pressure, and thereby permits the bearing a to remain in contact with the rail base in close relation to the edge thereof.

In the application of the anchor to the rail base, it is first preferably positioned, as shown in Figure 1, the end of the terminal portion engaging the fillet 17 of the rail at the location b, and the end of terminal portion 32 resting against the under-surface 13 of the rail. A driving force may be applied in the direction indicated by the arrow f in Figure 1, as by means of a maul, thus causing the anchor to be distorted, the loop portion 34 being initially distorted as a result of this blow to such an extent that the terminal portion 32 is projected beyond the flange edge surface 21, and is thus enabled to move upwardly into the position into which it is shown in Figure 2, the intermediate portion 31 preferably being in spaced relation to the rail, likewise advanced laterally as the loop 34 is distorted under the force of the applying blow and moving in tight engagement with the rail under-surface. In this position the rail anchor in tending to assume its normal condition applies a strong gripping action to the rail, particularly diagonally between the terminal portion 32 and the portion engaging the fillet of the rail, also between the intermediate portion and the last mentioned portion. Thus it will be seen that there is a strong gripping action on the rail by the anchor substantially horizontally and at the same time a well distributed reactionary force gripping the rail in a vertical direction.

As thus applied, the holding force of the anchor is very great and its tendency to tilt in service is minimized. In the event that abnormal forces are applied to move the rail longitudinally and cause the tilting of the anchor the vertical forces aforesaid would return the anchor to its normal position after such abnormal forces have been removed.

In the original fabrication of the anchor for use on a rail the distance, which is the shortest distance between the intermediate portion 31 and the terminal portion 30, is substantially less than the distance between the surfaces of the rails with which they respectively engage after the anchor is applied to the rail. The angle Y between the under-surface 13 and the rail flange upper-surface 14 is 14 degrees for most rails, the approximate angle between the under-surface of the anchor portion 30 at location a and the upper-surface of the intermediate portion 31, which is indicated at X in Figure 1, will be approximately ten degrees for an anchor constructed substantially as shown.

As the anchor is driven into position by a blow which develops the force F, the terminal end of portion 30 is further separated from the intermediate portion 31, these portions being sprung apart by the rail flange, and the anchor, particu-

larly the loop portion 34, being placed under stress. As thus distorted, the anchor will remain in position indefinitely, constantly gripping the rail base and preventing movement of the rail relative to the tie to which the anchor is associated, all without the occurrence of any substantial tilting.

Having thus described our invention, what we claim as new and desire to secure by Letters Patent is:

1. A rail anchor comprising a bar of resilient metal bent to provide a terminal portion for overlying one base flange of a railroad rail, a portion providing a bottom bearing for engaging the bottom surface of the rail, a rail flange edge engaging terminal portion, a portion connecting the last mentioned portion with the portion for bearing against said bottom surface of the rail base, and a portion connecting the bottom bearing portion with said flange overlying terminal portion and forming a depending tie abutting loop, the said rail flange overlying terminal portion formed with spaced bearing surfaces located at different distances above said bottom bearing, one of said bearing surfaces for engaging an area on the inclined upper-surface of the rail flange immediately adjacent the outer edge of the flange and the other of said spaced bearing surfaces formed to exert resilient gripping pressure transversely of the rail against an area of the fillet at the base of the rail web and the said terminal portion being out of contact with the rail throughout the spacing between these areas, whereby a portion of said terminal intermediate the spaced bearing surfaces is flexed downwardly toward the inclined top surface of the rail base during tilting of the anchor about said bottom bearing as an axis extending transversely of the rail and the said spaced bearing surfaces maintain their seating contacts independently of each other on said fillet and on the inclined top face of the underlying base flange immediately adjacent the edge thereof during said tilting of the anchor about said bottom bearing.

2. A rail anchor comprising a resilient metal strip of rectangular cross section which, includes a terminal portion for overlying one base flange of a rail, an intermediate portion providing a bottom bearing for engaging the undersurface of a rail base, approximately midway between the edges thereof, a rail flange edge engaging terminal portion having a lip rounded on its upper surface to fit over the upper corner portion of a rail base flange, a portion connecting the intermediate portion to the rail flange edge engaging portion, and a curved portion connecting the said intermediate portion and said rail flange overlying terminal portion and forming a depending tie engaging loop to be forcibly distorted by a rail flange when the anchor is driven onto a rail base and to thus cause the said terminal portion and intermediate portion to strongly grip between them the rail base and to cause the rail flange edge engaging portion to engage the edge of the opposite rail flange, the said rail flange overlying terminal portion formed with spaced bearing surfaces located at different distances above said bottom bearing, one of said spaced bearing surfaces engaging an area on the inclined upper surface of the rail flange immediately adjacent the outer edge of the flange and the other of said spaced bearing sur-

faces formed to exert resilient gripping pressure transversely of the rail against an area of the fillet at the base of the rail web and the said terminal portion being out of contact with the rail throughout the spacing between these areas, whereby a portion of said terminal intermediate the spaced bearing surfaces is flexed downwardly toward the inclined top surface of the rail base during tilting of the anchor about said bottom bearing as an axis extending transversely of the rail and the said spaced bearing surfaces maintain their seating contacts independently of each other on said fillet and on the inclined top face of the underlying base flange immediately adjacent the edge thereof during said tilting of the anchor about said bottom bearing.

3. A rail anchor comprising a resilient metal strip which, includes a terminal portion for overlying one base flange of a rail, an intermediate portion providing a bottom bearing for engaging the undersurface of a rail base, approximately midway between the edges thereof, but only at a location beyond the inner end of said terminal portion, a rail flange edge engaging terminal portion, a portion connecting the intermediate portion to the rail flange edge engaging portion, and a curved portion connecting the said intermediate portion and said rail flange overlying terminal portion and forming a depending tie engaging loop to be forcibly distorted by a rail flange when the anchor is driven onto a rail base and to thus cause the said terminal portion and intermediate portion to strongly grip between them the rail base and to cause the rail flange edge engaging portion to engage the edge of the opposite rail flange, the said rail flange overlying terminal portion being formed with spaced bearing surfaces located at different distances above the bottom bearing and exerting lever grips of different tenacity on the rail during the exertion of said lever grips, one of said spaced bearing surfaces for engaging an area of the rail flange upper-surface immediately adjacent the outer edge of the flange and the other of said spaced bearing surfaces formed to engage an area of the fillet at the base of the rail web and the said terminal portion being out of contact with the rail throughout the spacing between these areas, whereby a portion of said terminal intermediate the spaced bearing surfaces is flexed downwardly toward the inclined top surface of the rail base during tilting of the anchor about said bottom bearing as an axis extending transversely of the rail and the said spaced bearing surfaces maintain their seating contacts independently of each other on said fillet and on the inclined top face of the underlying base flange immediately adjacent the edge thereof during said tilting of the anchor about said bottom bearing.
